UNITED STATES PATENT OFFICE.

FRIEND L. SPENCER AND THOMAS JONES, OF ROCHESTER, NEW YORK.

CHAPLET.

Application filed August 29, 1923. Serial No. 660,033.

To all whom it may concern:

Be it known that we, FRIEND L. SPENCER and THOMAS JONES, both citizens of the United States, residing at Rochester, in the 5 county of Monroe and State of New York, have invented certain new and useful Improvements in Chaplets; and we do hereby declare the following to be a full, clear, and exact description of the same, reference being had to the accompanying drawing, forming a part of this specification, and to the reference numerals marked thereon.

Our present invention relates to molding, and more particularly to chaplets such as 15 are used for supporting a core in a mold and it has for its object to provide a simple construction of metallic chaplet which can be produced at a low cost and that will hold itself firmly in position under the weight of 20 the core. Further objects of the invention are to firmly anchor the chaplet in the sand so that a sustained position will be assured and to dispose of it in such manner that when melted by the incoming metal it will 25 be readily absorbed. To these and other ends the invention resides in certain improvements and combinations of parts all as will hereinafter be more fully described, the novel features being pointed out in the 30 claims at the end of the specification.

In the drawing:

Figure 1 is a vertical sectional view through a molder's flask containing a mold provided with a core supported by a plurality of chaplets constructed in accordance therewith and illustrating one embodiment of our invention;

Figure 2 is a perspective view of one of the anchoring pieces;

Figure 3 is a perspective view of the metallic chaplet, and;

Figure 4 is a sectional view taken longitudinally of the chaplet;

Similar reference numerals throughout 45 the several years indicate the same parts.

Some of the usual difficulties experienced in the use of chaplets are maintaining the supporting head at just the right degree of projection from the sand, and keeping it upright or normal to the surface of the core that it is used to support. In the practice 50 of our invention, aside from improving the metallic chaplet itself we support it in an anchoring body that holds it firmly and that 55 has a large area of contact in the surround-

ing sand, so that none of the ordinary jars and stresses are apt to displace it.

Referring more particularly to the drawing 1 indicates the bottom board, 2 the drag and 3 the cope of a simple form of molder's 60 flask in which a mold 4 has been made. The core 5 for this mold is shown supported by four of our improved chaplets, each consisting of a supporting head 6, a shank 7 and a shoulder 8. The head engages the 65 core while the shoulder rests against the wall of the mold and gives a broad support that defines the degree of projection of the head and, hence the thickness of the cast shell. The shank 7 is ordinarily simply pressed 70 into the sand but we provide a firmer support by using a plurality of anchoring blocks 9, the surfaces of which are flush with the wall of the mold on one side and which contain bores 10 normal to such surfaces. At the mouth of the bore is a counter-sunk portion 11 to receive the shoulder flange 8 of the chaplet. These anchoring 75 blocks may be of various sizes and shapes and may be individual to each chaplet as shown in the cope or a plurality of chaplets may be supported in one anchor block as shown in the drag. The blocks are preferably of sand but are self sustaining and 80 firmer than the surrounding sand of the flask and are preferably made in the same manner as an ordinary core, that is molded with a suitable binder and baked so that they are ultimately frangible but will hold their form 85 for ordinary purposes. One of the individual blocks is shown separately in Figure 2 of frusto-conical shape so that it will lock itself in the sand in the manner of a dovetail and not fall into the mold when inverted as shown in the cope portion of Figure 1. 90 The shank portion 7 of the chaplet being inserted in the bore 10 and the flange or shoulder 8 lodged in the countersunk portion 11, the device is firmly held against lateral displacement and maintains the core 95 5 accurately spaced in the walls of the mold without fear of disarrangement.

We prefer to plate the chaplet with an easily fusible metal such as tin in order to cause it to melt quickly and fuse with the 100 casting and at the same time we utilize the tin bath as a securing means for the flange 8. This flange as shown in Figure 4 is preferably constituted by a washer slipped over the shank 7 to a point at the desired dis- 110

tance from the head 6 and the tin plate or protective coating indicated at 12 in Figure 4 acts as a solder to fix the washer in place.

5. We claim as our invention:

1. A chaplet embodying a supporting head having an integral shank and a shoulder intermediate the shank consisting of a separate washer encircling the same, the whole 10 structure carrying a coating of a more readily fusible metal by which the washer is secured to the shank.

2. The combination with a self sustaining non-metallic anchoring piece adapted to be imbedded in the molding sand and having greater cohesive properties than the latter, of a chaplet embodying a shank supported in such anchoring piece, a head projecting therefrom and an intermediate 15 shoulder abutting the anchoring piece.

3. The combination with a self sustaining non-metallic anchoring piece adapted to be

imbedded in the molding sand and having greater cohesive properties than the latter, said anchoring piece being provided with a bore, of a chaplet embodying a shank supported in such bore, a head projecting therefrom; and an intermediate shoulder abutting the anchoring piece at the mouth of the bore.

4. The combination with a self sustaining non-metallic anchoring piece adapted to be imbedded in the molding sand and having greater cohesive properties than the latter, said anchoring piece being provided with a bore and countersunk at the mouth of the bore, of a chaplet embodying a shank supported in such bore, a head projecting therefrom, and an intermediate shoulder occupying the countersunk portion of the anchor- 30 35 40 ing piece.

FRIEND L. SPENCER.
THOMAS JONES.
